UNITED STATES PATENT OFFICE.

WINTHROP MARTIN BAKER, OF WALTHAM, MASSACHUSETTS.

DESIGN FOR A DISPLAY-STAND.

SPECIFICATION forming part of Design No. 27,314, dated July 6, 1897.

Application filed May 12, 1897. Serial No. 636,242. Term of patent 14 years.

To all whom it may concern:

Be it known that I, WINTHROP MARTIN BAKER, a citizen of the United States, residing at Waltham, in the county of Middlesex and 5 State of Massachusetts, have invented and produced a certain new and original Design for Display-Stands, of which the following is a specification, reference being had therein to the accompanying drawings.

10 In the drawings, Figure 1 is a perspective view of a display-stand embodying my design, and Fig. 2 is a side elevation of the same.

In my design the stand is rectangular in plan. The sides 1 are perpendicular and 15 have an upper edge of the following contour: From the upper rear corner the upper edge of each side runs horizontal a short distance, then drops vertically about an equal distance,

then slopes obliquely nearly to the bottom, and then runs horizontal to the front edge of 20 the stand.

The top of the stand comprises the horizontal plane 2, the vertical plane 3, the long oblique plane 4, and the horizontal plane 5. The oblique plane 4 is crossed at intervals by 25 raised ribs or ridges 7 7.

What I claim is—

The design for a display-stand, substantially as shown and described.

In testimony whereof I affix my signature 30 in presence of two witnesses.

WINTHROP MARTIN BAKER.

Witnesses:

LEPINE HALL RICE,
OSCAR F. HILL.
